UNITED STATES PATENT OFFICE.

JOHN P. FERRITER, OF OCEANPORT, AND WESLEY T. GUEST, OF EATONTOWN, NEW JERSEY.

ALTERNATING-CURRENT TELEGRAPH SYSTEM.

Application filed September 3, 1925. Serial No. 54,290.

The general object of this invention is to provide a new and efficient method of utilizing alternating current for telegraph purposes.

5 A more specific object is to provide a means of utilizing the positive half cycles of the transmitted alternating current to operate a telegraph relay at the distant station and the negative half cycles to operate a 10 second telegraph relay at the distant station, thus providing two independent circuits on the same wire and with the same alternating current power.

With the foregoing and other objects in view, the invention consists in the combination and arrangement of parts hereinafter set forth, certain embodiments thereof being illustrated in the accompanying drawings, in which:

20 Figure 1 is a diagrammatical showing of one form of the invention employing an alternating current.

Figure 2 is a diagrammatical showing of a modified form of the invention employing a 25 direct current.

In Figure 1, AC represents a source of alternating current, which may be of any desired audible frequency and preferably of a sinusoidal form. T, T₁, T₂, T₃, and T₄ represent 30 transformers.

Terminal 1 of secondary winding S of transformer T is connected to the grid G of a three electrode power vacuum tube V and terminal 2 of secondary winding of 35 transformer T is connected to the filament of the same vacuum tube and to the lever of key K in parallel. Terminal 2 of secondary winding S₂ of transformer T₂ is connected to the grid G₁ of power vacuum tube V₁ and terminal 1 of the secondary winding of 40 transformer T₂ is connected to the filament of vacuum tube V₁. Terminal 1 of secondary windings S₁ of transformer T₁ is connected to the back contacts of keys K and 45 K₁ in parallel, and terminal 2 of the same secondary winding is connected to the front contacts of keys K and K₁ and to the earth E in parallel. Plate PL₁ of tube V₁ is connected to the lever of key K₁. Plate PL of 50 vacuum tube V and the filament of vacuum tube V₁ are connected in parallel to the junction point 1 of equal resistance arms R and R₁, each of which may have a value of from 500 to 1200 ohms. Terminal 2 of arm

R is connected to a telegraph line leading to 55 a distant station and there equipped with an arrangement of apparatus similar to the one we are describing. Terminal 3 of arm R₁ is connected to an artificial line composed of resistance AL and capacity CN, equal in 60 value to the resistance and capacity of the line and the associated apparatus at the distant terminal, thus providing for duplex operation in a manner well known. The artificial line is connected to the earth at E₁. 65

What has been described constitutes the transmitting apparatus and source of power. The receiving apparatus is bridged across terminals 2 and 3 of the bridge arms R and R₁, as is usual in bridge duplexes. Grid G₃ 70 of vacuum tube V₃ and the filament of vacuum tube V₂ are connected in parallel to the line at its junction 2 with resistance R. Grid G₂ of vacuum tube V₂ and the filament of vacuum tube V₃ are connected in parallel 75 to the artificial line at its junction 3 with resistance R₁. Plate PL₂ of vacuum tube V₂ is connected in series with relay RL, secondary S₃ of transformer T₃ and the filament of the same vacuum tube. In a similar 80 manner, plate PL₃ of vacuum tube V₃ is connected in series with relay RL₁, secondary S₄ of transformer T₄ and the filament of vacuum tube V₃. The primary windings of 85 transformers T₄ and T₃ are supplied with alternating current from the power leads AC₁, which may be identical with power leads AC.

The arrangement of apparatus we have described, when connected by a suitable wire 90 line to a similar arrangement of apparatus at a distant terminal, constitutes a means of transmitting four messages over a wire simultaneously, two in each direction. It may be operated manually or automatically. 95 We will describe its operation manually, by means of keys and reading sounders.

Figure 1 represents a telegraph duplex installation. By this we mean that, when a proper balance is obtained by adjusting AL 100 and CN, signals originating at the home station will not actuate the receiving instruments at the home station, but will actuate the receiving instruments at the distant terminal of the line. With a proper balance of the artificial line at the distant station, the signals originating at the distant station 105 will not affect the receiving instruments at

that station. In this way, transmission of signals may be accomplished in both directions simultaneously.

In ordinary duplex telegraphy, using direct current, it is customary to provide for the transmission of only two signals simultaneously, one in each direction. With our system, by the use of alternating current, we utilize the positive half cycles to operate one receiving relay and the negative half cycles to operate a second receiving relay, thus virtually providing for the passage of two signals in each direction at the same time and, in so doing, we actually double the message carrying capacity of an ordinary duplexed telegraph circuit. This is accomplished as follows:

We connect a suitable source of alternating current at AC, Figure 1. This may be of any desired audible frequency. In practice, we find that a sixty cycle alternating current is suitable for manual operation and for single channel or two channel multiplex printing circuits. A higher frequency is desirable where more than two multiplex channels are operated.

We will assume that keys K and K¹ are both resting on their back contacts. With alternating current passing through the primary windings of transformers T, T¹ and T², a current will be induced in their corresponding secondary windings. It will be noted that tubes V and V¹ are reversed with respect to each other and, as current can pass through a vacuum tube only when the plate is positive with respect to the filament, a current passing through secondaries S and S² will cause only one tube to operate, depending upon the direction of current through the secondaries. For example, a half cycle which would impress a negative potential upon grid G would cause grid G¹ to become positive, and a half cycle which would make G¹ negative would make G positive. In this way, one tube would operate during a positive half cycle and the other during a negative half cycle. It will be noted that the current induced in the secondary S¹ of transformer T¹ is always in phase with the current induced in secondaries S and S², so that it is always flowing in the proper direction to provide current for the plate circuits of tubes V and V¹ at the instant either tube is operative. With this explanation, it will be seen that with keys K and K¹ resting on their back contacts when grid G is made positive by a half cycle through S, a negative current will flow from E, through S¹, the back contact of K, through tube V, from filament to plate PL and to junction point 1 of R and R¹ where it divides, one half going through the artificial line to the earth and the other half going over the line to the distant station and to earth. On the other hand, the next half

cycle, which is in the opposite direction, will cause grid G¹ of tube V¹ to become positive and a positive current will flow from earth E, through S, back contact of key K¹, through PL1 to filament of V¹, to junction point 1 of R and R¹, where it divides, as did the previous half cycle. In this manner it will be seen that, when one key is open, positive pulses are transmitted and, when the other key is opened, negative pulses are transmitted. When both keys are open, positive and negative pulses follow each other in regular succession. When key K is closed on its front contact, it has the effect of connecting the plate circuit of tube V to the earth E, so that no current flows through it from transformer T¹, thus making tube V inoperative. Similarly, closing K¹ on its front contact connects the plate circuit of tube V¹ to earth at E and makes tube V¹ inoperative. In this manner, when both keys are closed, no current flows over the line. At the distant station, the signals are received as follows:

When both keys are closed on their front contacts at the transmitting station and therefore no current is received at the receiving station, there is no current flowing through the coils of relays RL and RL¹ and their armatures are held against the back contacts by retractile springs. This will operate sounders SN and SN¹. When key K is resting on its back contact at the transmitting station, a succession of negative pulses pass to the receiving station, making grid G² of tube V² positive with respect to its filament. This causes current to flow in its plate circuit and causes the armature of relay RL to respond to a series of impulses which will be the resultant of the frequency of the received impulses and that of the alternating current impressed on the plate circuit through transformer T². These impulses cause the armature of relay RL to vibrate and leave its back contact, which causes sounder SN to open. When key K¹ is resting on its back contact at the transmitting station, it causes a succession of positive pulses to reach the receiving station. These make the grid G³ of tube V³ positive with respect to its filament and cause relay contact RL¹ and sounder SN¹ to open. It will be seen that there are virtually two independent duplex circuits, one operating on the positive and the other on the negative half cycles of an alternating current.

While we have shown how we use alternating current in the plate circuits of the transmitting and receiving tubes, it will be readily seen that the same alternating current can be used to heat the filaments of the transmitting tubes. The alternating current supply for the plate circuit of the receiving tubes must be of the same frequency as the incoming current or it must be appreciably

different. Direct current may be used in the plate circuits of the transmitting and receiving tubes if desired. This arrangement is shown in Figure 2, in which the plate circuit batteries of the various tubes are represented by B, B¹, B² and B³. The resistance R² is of a value to compensate for the resistance of plate circuit battery B when key K is on its front contact. Resistance R³ acts similarly with respect to battery B¹ and key K¹.

One advantage of our system of alternating current telegraphy is that, by the use of filters, several different telegraph circuits may be operated over one wire. A second advantage is that, in an alternating current telegraph circuit, vacuum tube repeaters may be used. We describe a suitable vacuum tube repeater for this purpose in another patent application. A third advantage of our system of alternating current telegraphy is that it is secret.

What we claim is:

1. A system of telegraphy comprising a source of alternating current, means for utilizing the positive half-cycles of said current to operate a telegraph circuit and the negative half-cycles to operate a second telegraph circuit, said means comprising a pair of transmitting tubes, a pair of transformers each of which have their secondary windings connected to the grid of the adjacent tube, an intermediate transformer having its primary in parallel with said other transformers and said current source, keying means associated with said intermediate transformer for producing, through said secondary, negative pulses to affect a plate current in one of said tubes and positive pulses to affect plate current in said other tube.

2. A system of telegraphy comprising a source of alternating current, means for utilizing the positive half-cycles of said current to operate a telegraph circuit and the negative half-cycles to operate a second telegraph circuit, said means comprising a pair of transmitting tubes, a pair of transformers

each of which have their secondary windings connected to the grid of the adjacent tube, an intermediate transformer having its primary in parallel with said other transformers and said current source, keying means associated with said intermediate transformer for producing, through said secondary, negative pulses to affect a plate current in one of said tubes and positive pulses to affect plate current in said other tube, a receiving circuit including a distant line and an artificial line, a pair of tubes, a relay connected to the plate of each receiving tube and a transformer connected to each filament of said tubes.

3. A system of telegraphy comprising a source of alternating current, means for utilizing the positive half-cycles of said current to operate a telegraph circuit and the negative half-cycles to operate a second telegraph circuit, said means comprising a pair of transmitting tubes, a pair of transformers each of which have their secondary windings connected to the grid of the adjacent tube, an intermediate transformer having its primary in parallel with said other transformers and said current source, keying means associated with said intermediate transformer for producing, through said secondary, negative pulses to affect a plate current in one of said tubes and positive pulses to affect current in said other tube, a receiving circuit including a distant line and an artificial line, a pair of tubes, a relay connected to the plate of each receiving tube and a transformer connected to each filament of said tubes, an equal arm resistance bridge connected to said receiving and said transmitting circuit, said bridge being adapted to supply half of the transmitted current to said artificial line and thence to earth and the other half to said distant line.

In testimony whereof we affix our signatures.

JOHN P. FERRITER.
